Primary Examiner — Carol P Rademaker(74) *Attorney, Agent, or Firm* — James E. Piotrowski(57) **CLAIM**

The ornamental design for a bottle with cap, as shown and described.

DESCRIPTION

FIG. 1 is a top, front, right side perspective view of a bottle with cap according to a first embodiment of the new design; FIG. 2 is a front elevational view thereof, the rear elevational view being identical;

FIG. 3 is a right side elevational view thereof, the left side elevational view being identical;

FIG. 4 is a top plan view thereof, shown at an enlarged scale for clarity of illustration;

FIG. 5 is a bottom plan view thereof;

FIG. 6 is a top, front, right side perspective view of a bottle with cap according to a second embodiment of the new design;

FIG. 7 is a front elevational view thereof, the rear elevational view being identical;

FIG. 8 is a right side elevational view thereof, the left side elevational view being identical;

FIG. 9 is a top plan view thereof, shown at an enlarged scale for clarity of illustration; and,

FIG. 10 is a bottom plan view thereof.

The broken lines shown on the bottom surface in FIGS. 5 and 10 are included for the purpose of illustrating environmental structure and form no part of the claimed design.

1 Claim, 8 Drawing Sheets(56)
